John E. Bendix, of New York, N. Y.
Assignor to
E. B. Sexton & Co. of Baltimore, Md.
Letters Patent No. 909, Dated July 7, 1857.

The schedule referred to in these Letters Patent, and making part of the same.

To all whom it may concern:

Be it known that I, John E. Bendix, of the

Des. 909

SB

City, County and State of New York, have produced a new and original Design, for Gate fronts, and I do hereby declare that the following is a full, clear and exact description of the same; reference being had to the annexed drawing forming part of this specification, which shows an elevation of one half of the front; the design of the omitted portion being the same as represented; arranged in reverse order.

The center of the arch has an ornament of foliage A, from which issues on either side, foliage represented at B, C, & D. Above this foliage is, a raised sweep E, bearing foliage in bas-relief. The corners of the front have each an ornament in bas-relief composed of foliage a and b, and flowers c, d, e.

The vertical portions of the front, have each a pilaster P, fluted as shown at f; the capitals embellished with foliage G; and the base H, made ^{up} of mouldings as shown in the drawings.

Beneath each pilaster is a panel ornamented in bas-relief with a figure I, made up of foliage and scrolls.

The several ornaments above described have the design, configuration and arrangement set forth in the drawing.

I claim the design, configuration and arrangement of the several ornaments in bas-relief as herein described and set forth in the annexed drawing.

In testimony whereof, I have hereunto signed my name before two subscribing witnesses.
